CHARLES B. WARREN, OF WESTFIELD, MASSACHUSETTS, ASSIGNOR TO W. WARREN THREAD WORKS, OF WESTFIELD, MASSACHUSETTS, A CORPORATION OF MASSACHUSETTS.

SUPPORT FOR THREAD COPS.

Application filed December 15, 1924. Serial No. 755,951.

This invention relates to improvements in supports for thread cops of the general character commonly used to supply thread to high speed sewing machines and the like. 5 The invention is particularly designed for use in connection with a very common type of cop, having a hollow cylindrical cop tube, usually of cardboard or fibre, upon which the thread is wound to form the cop body. 10 As generally used, these cops do not rotate and are wound so that the thread may be readily removed therefrom by an upward and approximately axially-directed pull,—the cop remaining stationary as the thread 15 is unwound, as distinguished from the practice in slow speed machines of unwinding ordinary flanged spools by rotatively mounting them and removing the thread by a lateral and tangentially directed pull. Hence, 20 the cop tube lacks the end flanges, one of which would interfere with the removal of the thread in the manner contemplated. Due to the lack of such flanges, trouble is frequently experienced during the removal of 25 the thread from the cop, because a coil of thread may become loosened therefrom, drop to the bottom of the cop and become caught thereinunder. This results in breakage of the thread and interruption of the work. 30 Aside from this difficulty in operation, there is another difficulty which arises when the spools are removed or replaced on the machine, as is often necessary, as for example, when a change in color or kind of thread 35 is required. In handling the cop, the cop tube of which, as stated, lacks the confining end flanges of the old time spool, the coils may become loosened, deranged and tangled, which results in waste of time and frequent- 40 ly in considerable waste of thread. While the last named difficulty might be overcome by careful handling of the cop and particularly by securely fastening the end of the thread to the cop, as is done by the thread 45 manufacturer, before the cop is removed, it is, as a practical matter, not feasible to rely upon the exercise of care from the present day operatives.

This invention has for its object the elimination of the above described difficulties by the provision of a supplemental device, or holder, which can be easily attached to, or detached from, the cop tube and customarily is retained associated therewith until the cop

is used up, after which it can be applied to 55 another cop tube.

In this way, the thread manufacturer can supply a relatively small number of the supplemental devices to each user of thread and enable the latter to use, without difficulty, the cylindrical cop tubes, which are desirable, from the thread manufacturer's point of view, for their low cost, as distinguished from providing a permanent flange on one end of each cop tube. 60

More particularly, it is an object of the invention to provide a supplemental device or holder which consists of a base flange and an attached mandrel, the latter adapted to be inserted in the hollow cylindrical cop tube and the former engaged with the base of the cop, together with means for holding the mandrel and cop tube from separation in an axial direction, whereby the cop tube cannot accidentally fall off its holder or be unintentionally removed therefrom,—it being desired to avoid the difficulties above set forth, by retaining the cop on its holder at all times until it is completely used up. 70

Another object of the invention consists in the provision of a holder, of the general type described, in which the upper face of the base flange is concave so that only the outer periphery of the base of the cop tube contacts therewith and in which the cop tube is freely slideable on the mandrel, whereby the former can drop, or be drawn downwardly progressively as the thread is unwound from the cop and the diameter of the same decreases,—thereby maintaining 80 close contact between the outer periphery of the base of the cop and said base flange to prevent the thread from being caught therebetween. 85

In connection with the last two objects 90 the device, by means of which the mandrel and cop tube are retained in associated relation, may advantageously include a spring serving to perform the additional function of drawing the cop tightly against the concave base flange at all times. 95

Other objects and advantages will appear in the following description and in the illustrative embodiment of the invention in the accompanying drawings, in which:— 100

Fig. 1 is a sectional elevational view of a holder for the cop shown in associated relation therewith; 105

Fig. 2 is a plan view drawn to a smaller scale, of the holder as it appears before association with the cop;

Fig. 3 is an elevational view thereof;

Fig. 4 is a sectional plan view taken on the line 4-4 of Fig. 3;

Figs. 5 and 6 are top plan views showing the cop tube and mandrel in unlocked and locked positions, respectively; and

Fig. 7 is a small scale view showing, in somewhat conventional form, the manner in which the cop with its holder is mounted for the use above specified.

Referring to these drawings: the thread 5 is wound upon a hollow cylindrical core, or cop tube 6 in the usual and well known manner, conventionally represented in Fig. 7, thereby forming a cop or cop body 7 (Fig. 1), the end faces of which are usually square with respect to the axis of the cop tube and lie close to, but ordinarily not quite flush with the ends of the cop tube. This is the present standard commercial product which it is desired to continue to market but which has the disadvantages above set forth.

As a means for overcoming such disadvantages, I provide a supplemental device or holder shown in Fig. 3, which may be conveniently and quickly associated with the standard product in the manner shown in Fig. 1. The parts when thus associated, afford a sort of a spool which, although of several parts, is a spool in the sense that the cop and holder may be handled as one unit and inserted in place in the machine, or removed therefrom, with the same ease and in much the same manner as the ordinary cop is handled. In use, the unit shown in Fig. 1 rests upon a base *a* (Fig. 7), whereby it is supported in an upright position, and it is held from displacement by a fixed spindle *b*. The thread 5 is led upwardly from the cop body 7, through a guiding eye *c*, carried by a standard *d*, and thence passes in the usual manner to the machine (not shown). The cop and its holder remain stationary during the removal of the thread.

This holder comprises a mandrel 8, herein shown as having an opening 9 leading axially upward from its lower end to receive the spindle *b*, and a circular base flange 10, which is suitably fixed to the mandrel and may be, as shown, integral therewith. The mandrel freely fits within the cop tube 6 so that the latter can slide relatively thereto, as by gravity action when the parts are supported as shown in Fig. 7. Preferably, however, the cop tube is drawn downwardly with additional force and, to this end as well as to the end of holding the mandrel and cop tube together in a manner to permit quick and convenient detachment, I provide a spring 11. This spring, which is an

ordinary coil spring, is fastened at one end to the mandrel 8 and, as shown, has one end hooked to a pin 12 which passes diametrically through the mandrel and spans the passage 9, in which said spring is located. The other end of this spring is connected to a device on the top of the mandrel 8 which device is conveniently accessible and adapted to be drawn up and connected to the upper end of the cop tube.

Such device consists of a circular disc 13, of a diameter substantially equal to the outside diameter of mandrel 8, and an attached depending pin 14 which is slidably and rotatably mounted in the upper and closed end of the mandrel. The pin 14 is mounted to slide along and turn about an axis parallel with the axis of the mandrel but slightly spaced therefrom, whereby the disc 13 turns eccentrically with respect to the mandrel. This disc can be turned from a position wherein its periphery coincides with that of the mandrel, as shown in Fig. 5, to a position wherein it does not coincide, as shown in Fig. 6, and in the latter position it can overlie the upper end of cop tube 6, as shown. The lower end of pin 14 extends into the upper end of passage 9 and is connected to the upper end of spring 11, whereby the latter, through the intermediary of the pin and disc, tends to draw the cop tube downwardly. While the upper end of the spring might act directly on the upper end of the cop tube, the pin and disc form a more convenient means of connecting the spring to the cop tube. The lower end of pin 14 is provided with a flange 15 which, by abutment with the end closure of passage 9, limits the extent of its upward sliding movement, the downward sliding movement being limited by the abutment of disc 13 with said end closure. The disc is provided with a loop handle 16, one leg 17 of which extends through and below disc 13 and into a recess 18 formed by slabbing off the upper end of the mandrel. This leg 17 can be turned from the position shown in Fig. 4 by full lines to that shown in dotted lines and is arranged to abut the flat side wall 19 of recess 18 to limit the extent of the turning movement of the disc 13. The two extremes of the movement of disc 13 are shown in Figs. 5 and 6. The leg 17 is made long enough so that it cannot pass wall 19 even when pin 14 is fully drawn up.

The base flange 10 is provided with a concave upper face 20, the latter being inwardly dished toward the centrally disposed mandrel 8. Encompassing the latter is a circular groove 21 of a width such as to freely receive the lower end of the cop tube 6, when and in case, the latter ultimately descends far enough to render this necessary. The purpose of the groove is to insure that there is nothing to stop the downward progress

of the cop body 7 as it works gradually downward under the force of spring 11, as the thread is unwound and its diameter decreases. In this manner the outer periphery 5 of the base 14 of the cop is kept constantly and tightly in contact with the base flange 10 to effectually prevent a loose coil of thread from becoming caught therebetween at any time, whether the holder is in place 10 in the machine or removed therefrom. It should be pointed out that in practice the ends of the parallel wound cops are often uneven and usually bulge out, probably due to an undue amount of tension in the outer 15 courses of thread when the cop is wound. Thus, the lower end or the base 22 of the cop is usually a little rough and irregular and therefore a base flange, having an upper face which is square with the axis of the 20 mandrel, will not always suffice to overcome the difficulties described, because a projecting thread in the base 22 may hold the latter from contact with the base flange 10 at the vital place, namely, the outer periphery,— 25 where contact is essential to prevent entrance of and subsequent catching of the thread in under the cop body. The slant of the cup shaped base is designed to be sufficient to overcome the unevenness in the ends 30 of the cop body and retain contact at the periphery of the same in the outside courses of thread at all times.

In practical use, the cops are supplied by the thread manufacturer to the user in the 35 regular way. That is, they are wound on a cylindrical cop tube without any retaining end flange but they are wound tightly and the end of the thread is securely fastened so that no derangement of the thread 40 is liable to occur from ordinary handling. The thread user, as fast as a new cop is required, places it on the holder, a suitable number of which are supplied to him by the manufacturer, and fastens the cop tube 45 in place by lifting and turning disc 13 to the position shown in Fig. 6. Once the cop is thus associated with the holder, it is ordinarily retained in this relation until it is used up. That is, if it becomes necessary 50 to change the kind or color of thread in the machine, the cop is not removed from its holder but the two are removed as one unit and laid aside until later required. By so doing, derangement of the thread is unlikely 55 to occur during the removal, handling or replacement of the cop and trouble is avoided at such times as well as when the cop is in use in the machine.

The practical results of this invention are 60 that the thread manufacturer is enabled to retain his standard product and to continue to market it under the favorable conditions resulting from low manufacturing costs due to the use of the very simple and relatively inexpensive cop tube. He is able to main-

tain his standard product, and find an adequate market for it, by providing a limited number of the holders with which the cop can be used with satisfaction. The objections of the user are overcome at a considerably less cost to the manufacturer than would be the case if he has forced to provide even the simplest end flange on each cop tube. Moreover, the holder, by reason of its conical base flange and provision for keeping the base of the cop in contact therewith at its outer periphery only, works far better and gives better satisfaction than any such ordinary end flange which might be added to one end of each cop tube.

The invention has been disclosed herein, in an embodiment at present preferred, for illustrative purposes but the scope of the invention is defined by the appended claims rather than by the foregoing description.

What I claim is:

1. A support for a thread cop wound on a hollow cylindrical tube, comprising, a cylindrical mandrel adapted to be inserted in or removed from said tube and upon which said tube is freely slideable in the direction of its axis, an opening provided in said mandrel adapted to receive an upright spindle by which the cop is held in an upright position, and a concave base flange on said mandrel to engage the base of the cop near its outer periphery, whereby as the thread is unwound from the cop and its diameter decreases, the cop tube slides downwardly on said mandrel due to the concavity of said base flange and keeps the outer periphery of the base of the cop in contact with said flange.

2. A support for a thread cop wound on a hollow cylindrical tube, comprising, a cylindrical mandrel adapted to be inserted in or removed from said tube and upon which said tube is freely slideable in the direction of its axis, an opening provided in said mandrel adapted to receive an upright spindle by which the cop is held in an upright position, a concave base flange on said mandrel to engage the base of the cop near its outer periphery, and a spring connecting said cop tube and mandrel tending to draw the cop tube downwardly, whereby as the thread is unwound from the cop and its diameter decreases, the cop tube slides downwardly on said mandrel due to the concavity of said base flange and keeps the outer periphery of the base of the cop in contact with said flange.

3. A support for a thread cop wound on a hollow cylindrical tube, comprising, a cylindrical mandrel adapted to be inserted in or removed from said tube and upon which said tube is freely slideable in the direction of its axis, an opening provided in said mandrel adapted to receive an upright spindle by which the cop is held in an upright po-

sition, a concave base flange on said mandrel to engage the base of the cop near its outer periphery, and a spring connected to said mandrel and extending upwardly through said cop tube and detachably connected with the upper end thereof, whereby as the thread is unwound from the cop and its diameter decreases, the cop tube slides downwardly on said mandrel due to the concavity of said base flange and keeps the outer periphery of the base of the cop in contact with said flange.

4. A multi-part spool, comprising, a hollow cylindrical cop tube upon which the thread is wound, a cylindrical mandrel adapted to freely fit within said tube and permit the tube to freely slide relatively thereto in an axial direction, a base flange fixed to said mandrel and having its upper face dished inwardly toward the same, and a spring carried by said mandrel and extending upwardly through said cop tube and adapted to be detachably engaged therewith.

5. A multi-part spool, comprising, a hollow cylindrical cop tube upon which the thread is wound, a cylindrical mandrel adapted to freely fit within said tube and permit the tube to freely slide relatively thereto in an axial direction, a base flange fixed to said mandrel and having its upper face dished inwardly toward the same, and a spring carried by said mandrel and extending upwardly through said cop tube and adapted to be detachably engaged therewith, said dished upper face provided with a circular groove encompassing said mandrel and adapted ultimately to freely receive the lower end of said cop tube as the latter is drawn downwardly.

6. In combination, a mandrel adapted to be inserted in the opening of a cop tube and to permit said tube to slide axially thereon, a base flange carried by said mandrel, a member disposed at the upper end of the mandrel and mounted therein to turn from a position in which it permits free entrance of the mandrel into the cop tube to a position in which it overlies the upper end of said tube, said member being mounted in the mandrel to slide in an axial direction, and resilient means tending to draw said member toward the mandrel.

7. In combination, a mandrel adapted to be inserted in the opening of a cop tube and to permit said tube to slide axially thereon, a base flange carried by said mandrel, a locking disc disposed at the upper end of the mandrel and having a part slidably mounted therein and mounted to turn about an axis eccentric to the mandrel, and a spring connecting said part to the mandrel.

8. In combination, a mandrel adapted to be inserted in the opening of a cop tube and to permit said tube to slide axially thereon, a base flange carried by said mandrel, a locking disc disposed at the upper end of the mandrel and having a part slidably mounted therein and mounted to turn about an axis eccentric to the mandrel, a stop provided on said disc, abutments provided on said mandrel and cooperating with said stop to limit the extent of turning movement of said disc, and a spring connecting said part to the mandrel.

In testimony whereof I have affixed my signature.

CHARLES B. WARREN.
